UNITED STATES PATENT OFFICE.

WILLIAM SPARKS, OF JACKSON, MICHIGAN, ASSIGNOR TO THE SPARKS-WITHINGTON COMPANY, OF CLEVELAND, OHIO, A CORPORATION OF OHIO.

SIGNAL.

1,214,721.

Specification of Letters Patent.

Patented Feb. 6, 1917.

Application filed October 8, 1915. Serial No. 54,737.

To all whom it may concern:

Be it known that I, WILLIAM SPARKS, a citizen of the United States of America, and resident of Jackson, in the county of Jackson, in the State of Michigan, have invented new and useful Improvements in Signals, of which the following, taken in connection with the accompanying drawings, is a full, clear, and exact description.

10 This invention relates to certain improvements in signals of the cam actuated diaphragm type.

The primary object of the invention is to provide, in signals of this type, a new 15 and improved means for externally adjusting the related parts of the structure to vary the extent of forced vibration of the diaphragm and therefore the sound produced by the instrument.

20 Other objects and advantages will appear from the following description taken in connection with the accompanying drawings, in which—

Figure 1 is a side elevation of the signal. 25 Fig. 2 is a longitudinal cross section of the same with the resonator partially broken away. Fig. 3 is a cross section on line 3—3, Fig. 1. Fig. 4 is a side elevation partly in section, of a varied form of the invention. 30 Fig. 5 is a cross section on line 5—5, Fig. 4. Fig. 6 is a longitudinal cross section of a modified structure. Fig. 7 is a cross section on line 7—7, Fig. 6. Fig. 8 is a side elevation, partly in section, of another modified form of structure. Fig. 9 is a cross section of the complete signal of Fig. 8, taken upon a line indicated by 9—9 in said figure. Fig. 10 is a side elevation, partly in section, of another modified form of structure.

40 Fig. 11 is a cross section of the complete structure of Fig. 10, taken on a line corresponding to line 3—3, Fig. 1. Fig. 12 is a side elevation, partly in section, of a varied form of the invention. Fig. 13 is a 45 cross section on line 13—13, Fig. 12. Fig. 14 indicates a reversal of the cam structure of the remaining figures.

The invention, as disclosed in Figs. 1, 2 and 3, comprises a diaphragm 1 of sheet metal or similar material having its edge portion rigidly secured between the base 2 of an amplifier 3 and the marginal portion 4 of a diaphragm ring 5 having an opening 6, in this 55 illustration substantially circular and ee-

centric to a perpendicular to the diaphragm 1 passing through the wear-piece 7, positioned preferably substantially centrally of the diaphragm and rigidly secured to the same in any suitable manner.

The opening 6 is adapted to receive the boss 8 formed upon the end of a motor case 9 and the armature shaft 10 of the motor, and in this illustration the boss is of somewhat less diameter than the opening 6 so that the same is adapted for transverse movement therein. The motor case 9 carries the usual pole pieces and field coils 11, and is provided at its rear end with a cross bar 12 having an adjustable bearing 13 for the rear end of the motor shaft.

The armature shaft 10 has a washer or ring 14 mounted thereon and adapted to substantially contact with the inner wall of the motor casing 9, and the adjustable bearing 13 serves to hold the motor shaft in such position that the washer is in substantial contact with the case to prevent rattling of the armature shaft during operation of the motor, and to prevent the armature shaft from moving forwardly when the horn is tilted, whereby the cam teeth 15 upon rotor 16 mounted 85 upon the armature shaft 10 would be interlocked with the wear-piece 7 upon the diaphragm.

It is impossible in commercial manufacture to form the parts, particularly the armature shaft 10, of exactly the same length in every case, and it is likewise practically impossible to mount the washer 14 and the armature 17 and commutator 18 upon the shafts at exactly the same predetermined points, and the adjustable bearing 13 compensates for these differences in size and relative position of the parts and holds the armature shaft 10 confined against movement in either direction. It will be apparent that such an end-thrust bearing used in conjunction with a washer 14 is not adapted for, and cannot be used in, the completed structure as a means for varying the overlap of the cam teeth 15 upon the wear-piece 7, as the washer 14 prevents movement of the cam toward the diaphragm. The case 9 also carries suitable brushes 18, conductor fingers 19, and terminals 110

—20—, preferably of a construction similar to that shown in my co-pending application Serial No. 861,220 filed September 11, 1914, for electrically operated horns.

6 In order to vary the forced vibration of the diaphragm and, therefore, the volume and character of sound produced by the signal, I utilize a rotor —16— in which the cam teeth have their effective edge portions disposed at an angle to the diaphragm, and in combination with such a cam I provide 10 means for moving the armature shaft laterally of its axis whereby the point of contact of the wear-piece with the cam teeth is varied radially of the rotor, thereby varying the overlap of teeth upon the wear-piece to vary the extent of forced vibration of the diaphragm.

Various structures may be utilized for 20 moving the armature shaft —10— carrying the rotor, transversely of its longitudinal axis, and in Figs. 1, 2 and 3, I have shown the front wall of the motor case —9— as provided with a projecting flange —21— 25 preferably extending, as shown, more than half the circumference of the motor case. This flange is provided with a circular opening —22— at one end and a series of slots —23— substantially concentric with said 30 opening, progressively increasing in length as their distance from the opening —22— increases. The motor case is then secured to the ring —5— by means of threaded screw or bolt —24— engaging the flange 35 —21— and lying in the opening —22— and having a threaded engagement with an interiorly threaded opening in the ring —5—. This screw —24— forms a pivot on the ring —5— about which the motor case as 40 a whole, carrying the rotor —16—, moves. A suitable series of screws or bolts —25— are engaged with the slots —23— and have a threaded relation with interiorly threaded openings in the ring —5—. By loosening 45 the screws —25—, the motor case may be rotarily moved about the axis —24— until the desired overlap of the teeth —15— upon the wear-piece —7— is attained. The screws may then be tightened to hold the motor 50 case in its adjusted position.

It will be readily apparent that the movement of the motor case, and the parts carried thereby, rotarily about the axis —24—, which axis is eccentric to the axis of the case, causes a movement of the case and armature shaft laterally of the longitudinal axis of said shaft, thereby radially varying the point of contact of the cam teeth with the wear-piece —7—, and that by varying 55 the point of contact the degree of overlap and the forced vibration of the diaphragm are likewise varied.

In Figs. 4 and 5, a slightly varied form of construction is shown, in that the motor 60 case —9— is directly laterally movable as

a whole, rather than rotarily movable to effect a lateral movement, and for this purpose the case is provided with the flange —21—, which may or may not be continuous, such flange being provided with a series 70 of parallel extending slots —23— for the reception of the screws or bolts —25— having a threaded relation with the ring —5—. By loosening the screws, the motor case and armature shaft carried thereby are directly moved laterally of the axis of the shaft to radially vary the point of contact of the cam teeth of the rotor with the wear-piece. The screws may be tightened to hold the motor in any desired position of adjustment. 80

In Figs. 6 and 7, another modified form of the invention is shown, in which the ring —5— is provided with a circular flange —26— adapted to fit over the exterior of 85 the adjacent end of the motor case —9— and having circumferentially extending slots —27— for the reception of screws —28— having a threaded engagement with the motor case —9—. In this illustration, the armature shaft —10— is positioned eccentrically of the case —9— so that rotation of the case —9— within the ring —5—, which ring is rigid with the diaphragm, moves the armature shaft and rotor carried thereby 90 laterally of the axis of the shaft to radially vary the point of contact of the teeth of the cam with the wear-piece. The screws —28— may be loosened and any degree of adjustment attained by rotation of the case —9— 95 in the ring —5—, and the screws may then be tightened to retain the parts in their desired position of adjustment.

In Figs. 8 and 9, another modified form of structure is shown, the ring —5— being provided with the flange —26— and slots —27— for the reception of screws —28— engaged with the motor case —9—. In this illustration, however, the armature shaft is concentric with the main portion —29— of 100 the motor case, and the end portion —30— of such case engaged with the flange —26— has a portion of its exterior surface ground away or is, in the original operation of production, circularly shaped about an axis eccentric to the axis of the motor shaft which is coincident with the axis of the main portion —29— of the motor case. It will be apparent that rotation of the motor case —9— with the ring —5— will move the 105 shaft —10— laterally of its axis and radially vary the point of contact of the cam teeth with the wear-piece, due to the eccentricity of the motor shaft with respect to the end portion —30— of the case, which end 110 portion engages the flange —26— and determines the axis of movement of the case —9—.

In Figs. 10 and 11, a further varied form of the invention is shown, in that the motor 115

case —9— is of somewhat less diameter than the flange —26— so that the case may bodily be moved laterally within the flange to radially vary the point of contact of the cam teeth with the wear-piece. By adjusting the screws —31—, which have a threaded relation with the flange —26— and which may either bear against the exterior of the motor case or may have a threaded relation there-
 10 with, the motor case may be moved in any desired direction relative to the flange —26—, whereby the motor shaft —10— is moved transverse of its longitudinal axis to radially vary the point of contact of the cam teeth with the wear-piece.
 In Figs. 12 and 18, a modified form of the invention is shown. In this structure the motor case is provided with a projecting boss —32— in which the motor shaft —10— is journaled and through which said shaft extends. The boss —32— is provided with laterally extending brackets —33— at its forward end, which brackets are provided with pintles —34— journaled in ears —35—
 15 projecting rearwardly from the ring —5—. The wear-piece —7— is disposed substantially diametrically of the diaphragm, and the axes of the pintles —34— preferably lie in the same diameter of the diaphragm.
 20 The rotor —16—, in this instance, may be shaped as shown to constitute a combined wheel and face cam so that the rotary movement of the motor about the axes of the pintles —34—, although varying the point of contact of the wear-piece with the teeth of the rotor, will not vary the degree of overlap of said parts, thereby producing the same extent of forced vibration of the diaphragm in any movement of the motor
 25 from a horizontal to a vertical position of the armature shaft thereof. It will be apparent, however, that the teeth of the rotor may be shaped in various ways to vary the degree of overlap of the same upon the wear-piece as the motor is rotated on the pintles —34—. This structure is very advanta-
 30 geous, even where the movement of the motor from vertical to horizontal position does not affect the extent of forced vibration of the diaphragm, due to the fact that it may be made to fit an available space when permanently assembled and positioned for use, as upon a motor vehicle. And for the purpose of holding the motor in any desired
 35 position relative to the diaphragm, the ring —5— is provided with a semi-circular, rearwardly projecting bracket —36— having a slot —37—concentrically disposed with respect to the axis of movement of the motor, said bracket lying in substantial contact with the boss —32— in any position of adjustment of the boss, and a suitable set screw —38— extends through the slot and has a threaded relation with an interiorly threaded seat in the boss —32—. The set screw may
 40 be loosened and the motor moved to any desired position of adjustment, either to accommodate itself to the available space or to provide variations in the forced vibration of the diaphragm, and the set screw may be tightened to hold the motor in the desired position of adjustment. Various means other than the one illustrated may be utilized for holding the motor in desired position.
 45 Fig. 14 illustrates a cam in which the curve or angle of the teeth is such that they approach nearer the diaphragm as they extend, preferably radially, outward from the axis of rotation, being a reversal of the cam shown in the other figures, in which the angular or curved disposition of the cam teeth causes their effective actuating portions to lie farther from the diaphragm as they extend outwardly from the radius of movement. With the cam of Fig. 14, a reversal of the effect of the adjustment of the cam of the other figures would be attained.
 50 Although I have shown and described several particular constructions and methods of operation as adapted for accomplishing the end in view, I do not desire to limit myself to any particular construction or method of operation, as many changes may be made in the details of construction and method of operation without departing from the spirit of this invention as set forth in the appended claims, the basic feature of which resides in varying the overlap of the cam teeth upon the diaphragm wear-piece by a movement of the means carrying said teeth transverse of its axis of rotation.
 55 What I claim is:—
 1. In a signal, a diaphragm having a wear piece, a motor including a case and having its armature shaft presented endwise toward the diaphragm, a rotor having teeth, and means for varying the overlap of said teeth upon the wear-piece by movement of said case in a plane substantially parallel with the diaphragm.
 2. In a signal, a diaphragm having a wear piece, a motor including a case and having its armature shaft presented endwise toward the diaphragm, a rotor having teeth, and means for varying the overlap of said teeth upon the wear-piece by a movement of said case in a plane perpendicular to the axis of rotation of said rotor.
 3. In a signal, a diaphragm having a wear piece associated therewith, a driving shaft presented endwise toward the diaphragm, a rotor on said shaft, and means for varying the overlap of said rotor upon said wear-piece by movement of said rotor in a plane perpendicular to its axis of rotation.
 4. In a signal, a diaphragm having a wear piece associated therewith, a driving shaft presented endwise toward the dia- 130

- phragm, a rotor on said shaft, and means for varying the overlap of said rotor upon said wear-piece by movement of said rotor in a direction substantially parallel with the 5 diaphragm.
5. In a signal, a diaphragm having a wear-piece associated therewith, a driving shaft presented endwise toward the diaphragm, a crown cam on said shaft and having its teeth angularly disposed with respect to the plane of the diaphragm, and means allowing movement of said cam solely in a direction transverse its axis of rotation to vary the degree of overlap of said cam upon 10 15 said wearpiece.
6. In a signal, a diaphragm having a wear-piece associated therewith, a crown cam adapted to rotate on an axis substantially perpendicular to the diaphragm having its teeth angularly disposed with respect to the plane of the diaphragm, and means allowing movement of said cam in a direction substantially parallel with the diaphragm to vary the degree of overlap of 20 25 said cam upon said wearpiece.
7. In a signal, a diaphragm having a wear-piece associated therewith, a rotary crown cam having its axis of rotation substantially perpendicular to the diaphragm and means permitting movement of the rotor solely in a direction transverse of its axis of rotation to vary its overlap upon the wear-piece.
8. In a signal, a diaphragm having a wear-piece associated therewith, a driving shaft presented endwise toward the diaphragm, a rotor on said shaft, means permitting movement of the rotor in a direction substantially parallel with the diaphragm 30 35 40 to vary its overlap upon said wear-piece.
9. In a signal, a diaphragm having a wear-piece associated therewith, a rotor, means permitting movement of the rotor about an axis substantially perpendicular to the diaphragm and at one side of the axis of rotation of said rotor, said movement varying the degree of overlap of said rotor on said wear-piece.
10. In a signal, a diaphragm having a wear-piece associated therewith, a rotor, means permitting movement of the rotor about an axis substantially perpendicular to the diaphragm at a point to one side of the wear-piece and eccentric to the axis of rotation of said rotor, said movement varying the degree of overlap of said rotor on said wear-piece.
11. In a signal, a diaphragm having a wear-piece associated therewith, a motor having its armature shaft presented endwise toward the diaphragm, a cam mounted upon said armature shaft, and means allowing movement of said motor transverse the axis of rotation of its armature shaft and 45 50 55 60 65 70 75 80 85 90 95 100 105 110 115 120 125 about an axis perpendicular to the diaphragm at a point to one side of the wear piece.
12. In a signal, a diaphragm having a wear-piece associated therewith, a rotary crown cam having substantially radially disposed teeth, and means allowing movement of the cam laterally of its axis to vary, radially of the cam, the contacting point of said wear-piece on said teeth.
13. In a cam actuated diaphragm signal, a diaphiragm having an impact surface and a rotor having cam teeth obliquely disposed, with respect to the plane of the diaphragm such rotor having a movement across its axis of rotation and about, an axis perpendicular to the diaphragm at a point to one side of the impact surface to vary the degree of overlap of said cam teeth upon said impact surface.
14. In a cam-actuated diaphragm signal, a diaphragm having a wear-piece associated therewith, and a rotor rotating in a plane substantially parallel with the diaphragm and having cam teeth obliquely disposed with respect to the effective contact surface of said wear-piece and means allowing movement of said rotor across its axis of rotation to vary the degree of overlap of said cam teeth upon said wear-piece.
15. In a cam-actuated diaphragm signal, a diaphragm having a wear-piece associated therewith, a rotor having cam teeth obliquely disposed with respect to the axis of rotation and in plane parallel to the diaphragm of said rotor, and means permitting movement of the rotor transverse its axis of rotation to vary its overlap upon said wear-piece.
16. In a cam-actuated diaphragm signal, a diaphragm having a wear-piece associated therewith, a driving shaft presented endwise toward the diaphragm, a rotor mounted on said shaft and having cam teeth obliquely disposed with respect to the effective contact surface of said wear-piece, said cam having a bodily movement radially of the wear piece to vary the point of contact of the wear piece on said cam teeth, and means permitting movement of the rotor transverse its axis of rotation and about an axis passing through the diaphragm at one side of the wear piece to vary its overlap upon said wear-piece.
17. In a cam-actuated diaphragm signal, a diaphragm having a wear-piece associated therewith, a driving shaft presented endwise toward the diaphragm, a rotor mounted on said shaft and having cam teeth obliquely disposed with respect to the effective contact surface of said wear-piece, and means permitting movement of the rotor transverse said effective contact surface to vary its overlap upon said surface.
18. In a signal, a diaphragm having a wear-

piece associated therewith, a rotor having cam teeth obliquely disposed with respect to the axis of rotation of said rotor, a rotary electric motor having its armature shaft presented endwise toward the diaphragm and upon which shaft said rotor is mounted, and means permitting movement of said motor about an axis eccentric to the axis of rotation of the armature shaft and passing

through the diaphragm at a point eccentric ¹⁰ of the wear piece for varying the overlap of said cam-teeth upon said wear piece.

In witness whereof I have hereunto set my hand this 27th day of September, 1915.

WILLIAM SPARKS.
